INTERNAL-COMBUSTION MOTOR.

973,800.

Specification of Letters Patent. Patented Oct. 25, 1910.

Application filed November 1, 1909. Serial No. 525,820.

To all whom it may concern:

Be it known that I, DONALD J. MCKINNON, of the city of Toronto, Province of Ontario, Canada, have invented certain new and useful Improvements in Internal-Combustion Motors, of which the following is a specification.

The problem of designing valve constructions for four-stroke cycle internal combustion motors is rendered much more difficult than the similar problem in steam engines owing to the greater pressure usually employed and the frequent presence of solids in the exhaust gases. Valves therefore which will answer admirably in the steam engine at present cannot be advantageously employed in an internal combustion motor owing to the difficulties of packing and lubrication. Among such valves constructions are rotary or oscillating valves such as used in Corliss engines, and my object is to devise means whereby such valves, or other valves which for similar reasons are now unsatisfactory, may be successfully employed in internal combustion motors and their resultant advantages obtained.

I attain my object by providing means for shutting off the pressure of the gases from the inlet and exhaust ports of the engine during the compression and explosion strokes of the motor, leaving to the valve system employed only the duty of closing the exhaust port during the suction stroke of the motor and of closing the inlet port of the motor during the exhaust stroke. The valves, being thus shielded, are relieved of the high pressure attained during the compression and explosion strokes of the motor which reduces the wear on the valves and makes packing and lubricating very simple problems.

Figure 1 is an end view of a motor constructed in accordance with my invention. Fig. 2 is a sectional plan view taken through the valves. Fig. 3 is a vertical section of a motor constructed in accordance with my invention. Figs. 4, 5 and 6 are fragmentary vertical sections showing different positions of the valves and sleeve and the crank centers of the operating means therefor.

In the drawings like letters of reference indicate corresponding parts in the different figures.

A is the cylinder of an engine which is in the main of ordinary construction and need not be particularly described.

B is the combustion chamber in axial alignment with the cylinder and of the same diameter. This combustion chamber is water jacketed as shown, and in order to prevent it having unduly great capacity its end C may project inwardly, as shown, somewhat in the same manner as the bottom of a wine bottle. In the end is a suitable opening or openings for the insertion of a spark plug or other attachments. In the sides of the combustion chamber are formed the inlet port D and the outlet port E. These ports are preferably of small length axially of the chamber but made of considerable width circumferentially as shown particularly in Fig. 2, in order to give the necessary capacity. Valves are provided for these ports of any suitable construction but preferably of the type hereinafter described.

Relative to the cylinder and combustion chamber a sleeve F is adapted to move. This sleeve is preferably made to slide within the cylinder and is provided with packing a of any suitable form preferably located adjacent to the upper edge of the sleeve which is made of increased thickness for that purpose. The piston G reciprocates within the sleeve F and is given a working fit therein, and will, of course, be provided with the ordinary packing. The function of the sleeve F is to shut off the ports of the combustion chamber during the compression and explosion strokes of the motor, and thus relieve the valve or valves from contact with the gases under pressure.

The necessary movements are imparted to the sleeve by the following mechanism: H is a crank shaft suitably journaled and driven from the main shaft of the motor by a suitable gearing adapted to give one revolution of the crank shaft H to two revolutions of the motor shaft I. I show a sprocket and chain gearing J for this purpose. A crank

K is formed on this shaft H, which, through the medium of the connecting rod L, pivotally connected to the crank and the sleeve, actuates the latter. In Figs. 3-4-5 and 6 the positions of the centers of this mechanism are indicated by round dots, the inner circle at the lower end of each figure indicating the path of travel of the center of the crank K. As the upper end of this sleeve opens up both the inlet and exhaust ports during both the suction and exhaust strokes, separate means must be provided to close the exhaust port during suction and the inlet port during exhaust. While various devices may be employed to accomplish this, I prefer to form in the walls of the combustion chamber valve casings adapted to contain the oscillating rotary inlet valve M and the oscillating rotary outlet or exhaust valve N. These valves are of the general type well known in connection with Corliss and similar steam engines. Each valve is provided with a stem b on which is secured an arm c. These arms are pivotally connected to the coupling bar O. One of the valve stems is also provided with an arm d. To this arm is pivotally connected one arm of a connecting rod P, the other end of which is pivotally connected with the crank Q on the crank shaft H. The desired oscillating rotary movement is thus imparted to the valves M and N. As the arc of oscillation of the exhaust valve N is preferably somewhat greater than the inlet valve M, it will be noted that the arm c on the stem of the exhaust valve is rather shorter than the arm c on the stem of the inlet valve, thus giving the desired variation in the respective arcs of travel.

In Figs. 3-4-5 and 6 the positions of the various centers of the operating mechanism for the valves M and N are indicated in round dots, the outer circle at the bottom of each figure indicating the path of travel of the crank Q. These figures respectively show the positions of the valves M and N and the sleeve F at the beginning of the suction stroke of the motor, the beginning of the compression stroke, the beginning of the explosion stroke and the beginning of the exhaust stroke.

It will be seen from these different views that the sleeve shuts off the ports during compression and explosion and thus relieves the exhaust and inlet valves of pressure, and that said valves respectively close the exhaust port during suction and the inlet port during the exhaust as desired.

It will be understood, of course, that I do not desire to limit myself to the precise construction and location of the means employed to relieve the valve or valves of pressure as various other devices might be employed to take the place of the sleeve which would answer the purpose of my in-

vention. The sleeve within the cylinder is described and also claimed in detail, as being at present considered the preferable form. It will also be clearly understood that the valve construction shown, while at present considered a preferable one, is not essential and any other suitable valve or valves might be employed instead.

In describing the action of the sleeve I use the expressions "open up the ports" and "shut off the ports" but it must be clearly understood that I only use these expressions in as far as they relate to the action of the sleeve itself in opening up the ports to give them free communication with the interior of the cylinder or in shutting them off from the pressure within the combustion chamber during the compression and exhaust strokes, the function of the sleeve being merely to act as a portcullis or shield to guard the valves from pressure during compression and explosion.

What I claim as my invention is,—

1. In a four-stroke cycle internal combustion motor the combination with the combustion chamber having inlet and exhaust ports formed in its walls of means for shutting off both of said ports during the compression and explosion strokes of the engine, and for opening up both during the exhaust and suction strokes; and means for closing the inlet port during the exhaust stroke and the exhaust port during the suction stroke.

2. In a four-stroke cycle internal combustion motor the combination with the combustion chamber having inlet and exhaust ports formed in its walls of means within the combustion chamber for shutting off both of said ports during the compression and explosion strokes of the engine, and for opening up both during the exhaust and suction strokes; and means external to the combustion chamber for closing the inlet port during the exhaust stroke and the exhaust port during the suction stroke.

3. In a four-stroke cycle internal combustion motor the combination with the combustion chamber having inlet and exhaust ports formed in its walls of means within the combustion chamber for shutting off both of said ports during the compression and explosion strokes of the engine, and for opening up both during the exhaust and suction strokes; and a separate rotary valve for each port adapted to open and close said ports.

4. In a four-stroke cycle internal combustion motor the combination with the combustion chamber having inlet and exhaust ports formed in its walls of means within the combustion chamber for shutting off both of said ports during the compression and explosion strokes of the engine, and for opening up both during the exhaust and suction strokes; and a separate oscillating rotary

valve for each port adapted to open and close said ports.

5. In a four-stroke cycle internal combustion motor the combination of a cylindrical combustion chamber having an inlet and an exhaust port in its sides; a movable sleeve adapted to open up both ports during the suction and exhaust strokes of the engine and to shut them off during the compression and explosion strokes; and means exterior to the combustion chamber for closing the inlet port during the exhaust stroke and the exhaust port during the suction stroke.

15. 6. In a four-stroke cycle internal combustion motor the combination of a cylindrical combustion chamber having an inlet and an exhaust port in its sides; a longitudinally movable sleeve adapted to open up both ports during the suction and exhaust strokes of the engine and to shut them off during the compression and explosion strokes; and means exterior to the combustion chamber for closing the inlet port during the exhaust stroke and the exhaust port during the suction stroke.

7. In a four-stroke cycle internal combustion motor the combination of a cylindrical combustion chamber having an inlet and an exhaust port in its sides; a sleeve longitudinally movable in the combustion chamber and adapted to open it and shut off said ports; and a separate valve for each port adapted to open and close said ports.

35. 8. In a four-stroke cycle internal combustion motor the combination of a cylindrical combustion chamber having an inlet and an exhaust port in its sides; a sleeve longitudinally movable in the combustion chamber and adapted to open up both ports during the suction and exhaust strokes of the engine and to shut them off during the compression and explosion strokes; a valve adapted to close the inlet port during the exhaust stroke; a valve adapted to close the exhaust port during the suction stroke.

9. In a four-stroke cycle internal combustion motor the combination of a cylindrical combustion chamber having an inlet and an exhaust port in its sides; a sleeve longitudinally movable in the combustion chamber and adapted to open up and shut off said ports; and a separate rotary valve for each port adapted to open and close said ports.

55. 10. In a four-stroke cycle internal combustion motor the combination of a cylindrical combustion chamber having an inlet and an exhaust port in its sides; a sleeve longitudinally movable in the combustion chamber and adapted to open up and shut off said ports; and a separate oscillating rotary valve for each port adapted to open and close said ports.

11. In a four-stroke cycle internal combustion motor the combination of a cylind-

rical combustion chamber having an inlet and an exhaust port in its sides; a sleeve longitudinally movable in the combustion chamber and adapted to open up both ports during the suction and exhaust strokes of the engine and to shut them off during the compression and explosion strokes; an oscillating rotary valve adapted to close the inlet port during the exhaust stroke; and an oscillating rotary valve adapted to close the exhaust port during the suction stroke.

12. In a four-stroke cycle internal combustion motor the combination of a cylindrical combustion chamber having an inlet and an exhaust port in its sides; a sleeve longitudinally movable in the combustion chamber and adapted to open up and shut off said ports; and means exterior to the combustion chamber for opening and closing said ports.

13. In a four-stroke cycle internal combustion motor the combination of a cylindrical combustion chamber having an inlet and an exhaust port in its sides; a sleeve longitudinally movable in the combustion chamber and adapted to open up both ports during the suction and exhaust strokes of the engine and to shut them off during the compression and explosion strokes; and means exterior to the combustion chamber for closing the inlet port during the exhaust stroke and the exhaust port during the suction stroke.

14. In a four-stroke cycle internal combustion motor the combination of a cylindrical combustion chamber having an inlet and an exhaust port in its sides; a sleeve longitudinally movable in the combustion chamber and adapted to open up and shut off said ports; a separate oscillating rotary valve for each port adapted to open and close said ports; a shaft geared one-to-two to the motor shaft; a crank on said shaft; a connecting rod pivotally connected to said crank and to the aforesaid sleeve; a crank on said shaft set at an angle to the aforesaid crank; an arm on each of said rotary valves; and a connecting rod pivotally connected to said second crank and to one of said arms.

15. In a four-stroke cycle internal combustion motor the combination of a cylindrical combustion chamber having an inlet and an exhaust port in its sides; a sleeve longitudinally movable in the combustion chamber and adapted to open up and shut off said ports, said sleeve being provided with a thickened portion adjacent its upper end; packing located in said thickened portion; and means exterior to the combustion chamber for opening and closing said ports.

16. In a four-stroke cycle internal combustion motor the combination with the combustion chamber having inlet and exhaust ports formed in its walls of controlling means for closing the exhaust port during

the suction stroke and the inlet port during the exhaust stroke; and means adapted, during the compression and explosion strokes, to act as a shield between the gases under pressure and the aforesaid port controlling means by closing communication between the ports and the combustion chamber.

Dated at Toronto, this 30th day of Oct. 1909.
